UNITED STATES PATENT OFFICE.

GLENN BASKERVILLE, OF CHARLOTTE, NORTH CAROLINA.

MAGAZINE FUSE-BLOCK.

SPECIFICATION forming part of Letters Patent No. 729,038, dated May 26, 1903.

Application filed June 19, 1902. Serial No. 112,302. (No model.)

To all whom it may concern:

Be it known that I, GLENN BASKERVILLE, a citizen of the United States, residing at Charlotte, in the county of Mecklenburg and State 5 of North Carolina, have invented certain new and useful Improvements in Magazine Fuse-Blocks, of which the following is a full, clear, and exact description.

This invention relates to magazine fuse-blocks for electric circuits, the object being to provide a construction whereby a fresh fuse will be automatically thrown into circuit to take the place of a destroyed fuse and to accomplish this by means of a simple and cheap 15 apparatus which shall be efficient and certain in operation.

My invention consists of the construction of a carriage having a tendency to move toward a pair of terminals, said carriage adapted to carry a plurality of fuses which are to be brought successively into position to bridge the gap between said terminals. Upon the destruction of a fuse the carriage at once 20 brings a new fuse into the same position previously occupied by the destroyed fuse, thereupon establishing the circuit after a very slight interruption.

My invention also comprehends a double construction wherein said carriage and other 30 parts are duplicated to provide fuses in both conductors of a circuit.

My invention will be described with reference to the accompanying drawings, in which—

Figure 1 is a plan of the multiple fuse-block complete. Fig. 2 is a side elevation of the same, and Fig. 3 is a detail of one of the posts or terminals with which the end of the fuse engages.

Referring to the drawings by letter, A represents a base of insulating material carrying at each corner a metallic block, (indicated by a and a' and b and b', respectively.) Mounted along the middle of the block on two posts 40 c² c³ at each end are two rails d and d', respectively, elevated from the face of the base and forming a guide or track upon which the fuses may slide, as hereinafter described. Near one edge of the base A are fixed two 45 posts e and e', to the upper end of which are pivoted two horizontal arms f and f', respectively. The free ends of these arms are pro-

vided with slots f², and each also carries a pin or stop f³, against which a spiral spring f⁴ presses in order to give the arm a tendency to turn. The springs are so adjusted with respect to the arms that one arm is given a tendency to move toward one end of the block, while the other is given a tendency to move toward the other end. On another post 55 g is fixed a cross-bar g', which overlies the two arms to act as a guard therefor and keep them in working position. The posts at the corners of the base are provided with binding-screws for the connection of line-wires 60 and are also provided on opposing faces with inclined surfaces a², overhung by lips a³. These surfaces approach each other toward the end of the base A and form between them a wedge-shaped space.

C and C' are two plates which I call "carriages." Each of them is provided with a pin c c', which when in working position project into the slots f² of the swinging arms f and f', respectively. To the under side of the carriage are fixed in any suitable manner a series of fuses I, the manner of fixing them in place, as shown, being by screws i, which pass through the carriage and into the fuse; but any suitable form of clamp or other device may be used for this purpose, the only essential point being that the fuses shall be arranged transversely of the plate and substantially parallel to each other and with a space between them and that their ends all 70 terminate in line. The carriage, with the fuses thus attached, is placed on the rails d d' in such a position that the first fuse of the series shall stand between the two posts a and a', with its ends resting in contact, respectively, with the inclined surfaces a² on 75 said posts, and being wedged into this position by the force of the spring acting upon the arm f, thus establishing good contact. Under this condition current flows through the first 80 fuse only. It will be seen that when the fuse is destroyed by an abnormally-high current the entire fusible strip will collapse and fall clear of the terminals, there being no support for it either at an intermediate point or 85 at the ends. The instant the fuse is destroyed the spring-arm moves the carriage, so that the next fuse in the series will be carried forward into the wedge-shaped space until it 90

makes contact at its extremities with the respective terminals. When this fuse is destroyed, another takes its place in the same manner as before, and the operation is repeated until the last fuse in the magazine is used, whereupon the carriage can be again loaded and returned to its place or another duplicate carriage, already loaded, inserted in the same position.

10 It will be seen that the carriage is entirely free to be moved either in a longitudinal or lateral direction, so that in case one end of a fuse strikes its terminal before the other the carriage may shift laterally to bring the other end of the fuse into contact and to maintain equal pressure at each point of contact.

15 It is obvious that my invention extends to the use of either a single or double block, and by this I mean either one or two carriages 20 with their corresponding sets of fuses.

Having described my invention, I claim—

A multiple fuse-block consisting of two terminals having opposing inclined faces forming a wedge-shaped space between them, a horizontal guideway arranged between said terminals, a plate or carriage to which a plurality of fusible conductors are attached, the said conductors resting upon the guideway, a pivoted arm engaging with said plate or carriage and a spring acting upon said arm 30 and tending thereby to slide the fusible conductors along the guideway toward the terminals, substantially as described.

In witness whereof I subscribe my signature in presence of two witnesses.

GLENN BASKERVILLE.
